ROTARY MACHINE

John S. Morgan, Jr., Hermosa Beach, and John D. Spalding, Los Angeles, Calif., assignors to The National Supply Company, Pittsburgh, Pa., a corporation of Pennsylvania

Original application March 1, 1937, Serial No. 128,468. Divided and this application December 5, 1939, Serial No. 307,626

2 Claims. (Cl. 255—23)

This invention relates to rotary machines of the type used in the drilling of wells, and is more particularly related to a rotary machine of the enclosed type constructed to meet the present demands of deep drilling operations.

This application is a division of our co-pending application, Serial No. 128,468, filed March 1, 1937, for Rotary machine, now Patent No. 2,205,269.

An object of our invention is to provide an enclosed rotary machine wherein a unitary pinion shaft assembly is provided and wherein the rotary machine is constructed in such a manner as to permit this assembly to be mounted with relation to the base and the table in such a manner that a more efficient structure of rotary machine may be had.

Another object of our invention is to provide a rotary machine of the enclosed type including a rotary table, a base upon which the rotary table is rotatably mounted, and a unitary pinion shaft assembly which is adapted to be assembled with relation to the table and the base in such a manner that the structure may meet the presently increasing demands for high speed table operation so that the pinion, of increased size requisite for such operation, may be properly positioned with relation to the table gear and held in proper alignment with relation to the base structures.

Other objects and advantages of this invention it is believed will be apparent from the following detailed description of a preferred embodiment thereof as illustrated in the accompanying drawing.

In the drawing:

Figure 1 is a side elevation of a rotary machine embodying our invention and shown partly in section, the section being taken substantially on line 1—1 as shown in Figure 2. This figure illustrates the position of the parts during assembly of the upper and lower sections of the base, the pinion and gear not yet being in mesh.

Figure 2 is a plan view of the lower base or closure structure of the rotary machine embodying our invention.

Figure 3 is a sectional end view taken substantially on the line 3—3 of Figure 2.

The rotary machine embodying our invention includes a rotary table 1 having a gear ring 2 secured thereto in any suitable manner. The table 1 is provided with a downwardly depending skirt 3 which extends through a vertical opening formed in the base 4. The base 4 is divided horizontally to form an upper base member 4^a and a lower base member 4^b. The upper

base member 4^a provides a bearing race 5 for the thrust bearings 6 upon which the table 1 is rotatably supported. An upthrust bearing 7 is carried by the upthrust bearing ring 8 carried by the skirt 3 of the table 1. A race 9 for the upthrust bearing 7 is supported by a downwardly depending section of the inner wall 10 of the base section 4^a. The upper base member or section 4^a is formed with the outer closing rim 11 forming an enclosure with the table 1 in which the bearings 6 and 7 are lubricated by any suitable means and enclosed against the admission of foreign matter. The outer annular rim 11 forms with the table 1 a labyrinth seal 12. The lower base member or primary section 4^b of the base may be, as is illustrated, cast integrally with the skids 13 upon which the rotary machine is supported. The lower base member 4^b is provided with an annular flange 14^b adapted for connection with the corresponding flange portion 14^a on the base portion 4^a.

The lower base member 4^b is also formed with the substantially rectangular closure portion 15 corresponding in plan to pinion shaft housing portion 16 of the upper base member or secondary section 4^a and provides a closure flange 17 adapted to cooperate with the closure flange 18 of the said portion 16 to form a fluid-tight closure and housing for the pinion shaft assembly 19. The flange 17 and the annular flange 14^b are preferably formed as one continuous surface.

The pinion shaft assembly includes a pinion 20 secured to the pinion shaft 21 in position to mesh with the ring gear 2 of the table 1. The pinion shaft assembly is provided at its outer end with a driving sprocket 22 which overhangs the base. Positioned between pinion 20 and sprocket 22 are bearing means for removably securing pinion shaft assembly in position as a unit upon the base closure section 4^b. There are provided two spaced bearings 23, 23 spaced along the shaft 21 positioned within suitable bearing housings 24 which are adapted to be removably secured to the lower base member 4^b by means of bolts 25. Interposed between the bearing housings 24 are suitable rotation lock members 26. The lower half of the base 4^b is formed to include an oil retaining closure 30 cooperating with the base member 4^a and enclosing section 16 of the base section 4^a.

The entire assembly of the rotary machine may be effected as follows:

The upper base member 4^a is assembled together with the table 1 by passing the skirt 3 through the base opening so that the same is

rotatably supported upon the bearing 6. The up-thrust bearing ring, together with the upthrust bearing 7 may be then moved in position and secured in position by any suitable means such as by the bolts 27. The pinion shaft assembly is positioned upon the lower base member 4^b as an assembled unit. The table 1 and the base member 4^a are then lowered in position with relation to the base member 4^b and the pinion shaft assembly and are secured in position through the medium of suitable bolts 28 completing the assembly and the enclosure.

There is also formed between the sections 4^a and 4^b a pinion shaft seal 29 at the outer end of the shaft 21, which seal is formed to permit of the small amount of vertical adjustment necessary for the shaft 21. It will be obvious that by use of suitable shims 30 interposed between the bearing housing 24 and the base flange 17 that adjustment of the pinion 20 with relation to the gear ring 2 may be had.

Having fully described our invention, it is to be understood that we do not wish to be limited to the details herein set forth, but our invention is of the full scope of the appended claims.

We claim:

1. In a rotary machine of the enclosed type, the combination of an upper base member having an annular upstanding wall, a table rotatably mounted on thrust bearings carried by said member and cooperating with the upstanding wall to form an annular chamber within the wall, a gear on the table within the chamber, a shaft having a pinion thereon adapted to drive the gear, bearings for rotatably supporting the shaft, a laterally extending drive shaft housing integrally joined to said annular upstanding wall below the upper limit thereof, a lower base member comprising an integral structure including parallel skid elements extending adjacent and parallel to the drive shaft housing, an oil retaining closure member extending between the skid elements below the drive shaft housing, a horizontal supporting flange surface on the lower base member, a mating surface on the upper base member adapted to rest on said flange surface and to be de-

tachably secured thereto, the laterally extending drive shaft housing and the oil retaining closure member being provided with cooperating parts adapted to meet along a horizontal joint when said mating surface and supporting flange surface are in contact, the shaft, pinion, and bearings being enclosed between the drive shaft housing and the oil retaining closure, whereby they may be removed in a direction transverse to the shaft axis upon separation of the upper and lower base members.

2. In a rotary machine of the enclosed type, the combination of an upper base member having an annular upstanding wall, a table rotatably mounted on thrust bearings carried by said member and cooperating with the upstanding wall to form an annular chamber within the wall, a gear on the table within the chamber, a shaft having a pinion thereon adapted to drive the gear, bearings for rotatably supporting the shaft, a laterally extending drive shaft housing integrally joined to said annular upstanding wall below the upper limit thereof, a lower base member comprising an integral structure including parallel skid elements extending adjacent and parallel to the drive shaft housing, an oil retaining closure member extending between the skid elements below the drive shaft housing, a central opening in the lower base member through which said table may extend, a substantially circular horizontal supporting flange on the lower base member encircling the said opening, a mating surface on the upper base member adapted to rest on said flange and to be detachably secured thereto, the laterally extending drive shaft housing and the oil retaining closure member being provided with cooperating parts adapted to meet along a horizontal joint when said mating surface and supporting flange are in contact, the shaft, pinion and bearings being enclosed between the drive shaft housing and the oil retaining closure, whereby they may be removed in a direction transverse to the shaft axis upon separation of the upper and lower base members.
